WHEEL COVER

George Albert Lyon, 13881 W. Chicago Blvd.,
Detroit, Mich.

Filed May 9, 1960, Ser. No. 60,498

Term of patent 14 years

(Cl. D14—30)

I claim:

The ornamental design for a wheel cover, substantially as shown.
